CLAIM

The ornamental design for tongs, as shown and described.

DESCRIPTION

FIG. 1 is a front and right side perspective view of tongs showing my new design;

FIG. 2 is a side elevation view thereof;

FIG. 3 is a top plan view thereof;

FIG. 4 is a front elevation view thereof;

FIG. 5 is a bottom plan view thereof;

FIG. 6 is a detail taken along line 6—6 of FIG. 2; and,

FIG. 7 is a front and right side perspective view thereof showing the tongs being gripped and holding a small food item.

The broken lines showing the hand and food item in FIG. 7 are for illustrative purposes only and form no part of the claimed design.
